(57) **CLAIM**

The ornamental design for an information handling system bezel, as shown and described.

DESCRIPTION

FIG. 1 is a top perspective view of an information handling system bezel showing our new design.

FIG. 2 is an exploded top perspective view of the information handling system bezel of FIG. 1.

FIG. 3 is a front elevation view of the information handling system bezel of FIG. 1.

FIG. 4 is an exploded front elevation view of the information handling system bezel of FIG. 1.

FIG. 5 is a rear elevation view of the information handling system bezel of FIG. 1.

FIG. 6 is an exploded rear elevation view of the information handling system bezel of FIG. 1.

FIG. 7 is a top plan view of the information handling system bezel of FIG. 1.

FIG. 8 is a bottom plan view of the information handling system bezel of FIG. 1.

FIG. 9 is a left elevation view of the information handling system bezel of FIG. 1.

FIG. 10 is a right elevation view of the information handling system bezel of FIG. 1; and,

FIG. 11 is a perspective view of the information handling system bezel of FIG. 1, shown with the remainder of an information handling system depicted in broken lines to illustrate an environment use.

All evenly-spaced broken lines are for environmental purposes and do not form part of the claimed design, or designate portions of the information handling system bezel that do not form part of the claimed design. All dash-dot lines form boundaries of the claimed design.

1 Claim, 7 Drawing Sheets
